DRY SHAVER

Clare E. Graves, Sioux Falls, S. Dak.

Application February 15, 1946, Serial No. 647,703

3 Claims. (Cl. 30—43)

1

This invention relates to power-operated hair clipping or shaving devices, and has for its general object to provide a simple, practical device of this kind having a comparatively narrow, rounded nose whereby it is especially adapted for clipping or shaving at difficultly accessible locations as, for example, under the arms and in corners between different parts of the anatomy.

More particularly, an object of the invention is to provide a device of the kind mentioned embodying a clipping element, or elements, in the form of a wheel, or wheels, and novel driving means between the same and an electric motor or other source of power housed within the device.

Another object of the invention is to provide a clipping wheel having pivotal cutting elements and spring means tending constantly to swing the same outwardly relative to the wheel to maintain them in cutting contact with the inner face of the slotted nose of the device.

With the foregoing and other objects in view, which will become more fully apparent as the nature of the invention is better understood, the same consists in a hair clipping or shaving device embodying the novel features of construction, combination and arrangement of parts as will be hereinafter more fully described, illustrated in the accompanying drawings and defined in the appended claims.

In the accompanying drawings, wherein like characters of reference denote corresponding parts in the different views:

Figure 1 is a central, longitudinal section through a hair clipping or shaving device, constructed in accordance with one practical embodiment of the invention.

Figure 2 is a section through the device at right angles to Figure 1.

Figure 3 is a view similar to Figure 2 illustrating an alternative form of the device; and

Figure 4 is a fragmentary side elevation of a cutting wheel having pivoted spring-pressed cutting elements.

Figure 5 is a side view of my improved dry shaver shown in Figure 3.

Figure 6 is a view similar to Figure 3, showing the dry shaver equipped with double cutting wheels and in which the cutting elements are spring pressed, to engage and form cutting engagement with the nose piece of the shaver.

Referring to the drawings in detail, first with particular reference to the form of the invention illustrated in Figures 1 and 2, A designates, generally the body of the device which may be molded or otherwise formed from plastic or other

2

suitable material, and which is hollow to contain an electric motor designated generally as B.

The body A may be formed of interfitting, separable parts 10 and 11 to permit convenient mounting of the motor B and the cutting mechanism therein and at the rear end of the device there may be suitable terminals 12 for electrically connecting the motor B to a source of current through the instrumentality of an extension cord.

10 The front end of the housing A has a nose-piece 13 of thin, sheet metal suitably mounted thereon and, in accordance with the invention, the front end portion of this nose-piece is rounded both in side elevation and in transverse section. Moreover, the said front end portion of said nose-piece is provided with numerous narrow slots 14 extending crosswise thereof for the admission thereto of hairs to be clipped.

Extending from the motor B into the nose-piece 13 are bearing elements 15 in which is journaled a shaft 16 which extends transversely relative to said nose-piece and the axis of which is coincident with the center of the side elevational curvature of the front end portion of said nose-piece. On said shaft is fixed a cutting wheel 17 having peripheral cutting elements or knives 18 the outer end portions of which conform in curvature to and engage the inner face of the transversely rounded slotted outer end portion of the nose-piece 13. Accordingly, rotation of said wheel is effective to clip any hairs which extend through the slots 14 into the nose-piece. In this connection it will be observed that the front end portion of said nose-piece is relatively thin to adapt it for use in corners and other difficultly accessible portions of the face and other parts of the anatomy.

On the shaft 16 is mounted a beveled gear 19, while on a shaft 20 driven by the motor B and 40 which may be journaled in one of the bearing elements 15 is mounted a bevel gear 21 which is disposed in mesh with said bevel gear 19. Accordingly, rotation of the shaft 20 is effective to rotate the shaft 16 and thereby rotate the cutting wheel 17 to cause its cutting elements or knives 18 to cooperate with the inner face of the front end portion of the nose-piece 13 to clip any hairs which may project through the slots 14 into said nose-piece.

50 In the use of the device, the motor B is started by closing of a suitable switch and the front end portion of the nose-piece 13 is placed against and moved over the surface from which hairs are to be clipped or shaved, the hairs entering the

slots 14 and being clipped by the cutting elements as knives 18.

Referring now to the form of the invention illustrated in Figures 3 and 5 of the drawings, it will be observed that the construction is generally the same as the Figure 1 and 2 construction, except that two cutting wheels 17', 17' are employed as distinguished from the single cutting wheel of the Figures 1 and 2 construction.

The cutting wheels 17', 17' are inclined forwardly and inwardly relative to each other and each cooperates with a related half-portion of the front end of the nose-piece 13'. They are mounted on shafts 16', 16' which are mounted, in turn, in a bearing element 15' extending into the nose-piece from the motor B' and they carry crown gears 19' with which meshes a bevel gear 21' on a shaft 20' which is driven by said motor and which may be journaled, for example, in the bearing element 15'.

Rotation of the motor-driven shaft 20' obviously is effective to rotate the cutting wheels 17', 17' in opposite directions to cause their knives 18' to cooperate most effectively with the inner face of the front end portion of the nose-piece 13' to clip hairs which extend into said portion through the slots 14' therein.

According to either form of the invention the cutting elements or knives may be pivoted to the cutting wheel by which they are carried and any suitable spring means may be provided to swing them outwardly so that they maintain operative contact with the inner face of the slotted front end portion of the nose-piece. Figure 4 illustrates such a construction, using a single cutting wheel. The cutting elements or knives 18a are pivoted to the cutting wheel 17a as indicated at 22 on axes parallel to the axis of rotation of said cutting wheel, and spiral spring 23 is interposed between each of the same and the cutting wheel. Said springs tend constantly to swing said cutting elements outwardly relative to the cutting wheel and thus operate to maintain the free ends of said elements or knives pressed against the inner face of the front end portion of the nose-piece for most effective cutting cooperation therewith. Figure 6 shows double cutting wheels 17a having spring biased cutting elements or knives 18a, which elements or knives are spring biased by the spiral springs 23a, so that said springs tend constantly to swing said cutting elements outwardly relative to the cutting wheels 17a and thus operate to maintain the free ends of said elements or knives pressed against the inner face of the front end of the nose piece for most effective cutting cooperation therewith.

From the foregoing description considered in connection with the accompanying drawings it is believed that the construction and operation of the present device will be clearly understood and its advantages appreciated. It is desired to point

out, however, that while only certain specific structural forms of the invention have been illustrated and described, the same is readily capable of embodiment in specifically different structural forms within its spirit and scope as defined in the appended claims.

I claim:

1. A hair clipping or shaving device comprising a body having a nose-piece of thin sheet metal, the front end portion of which is rounded both in side elevation and in transverse section and is provided with transverse hair-admitting slots, a pair of rotatable cutting wheels within said body disposed in forwardly and inwardly inclined relationship to each other, cutting elements carried by said wheels for cooperation with related portions of the inner face of the front end portion of said nose-piece, and a motor carried by said body and having a driving connection with said wheels.

2. A hair clipping or shaving device comprising a body having a nose-piece of thin sheet metal, the front end portion of which is rounded both in side elevation and in transverse section and is provided with transverse hair-admitting slots, a pair of rotatable cutting wheels within said body disposed in forwardly and inwardly inclined relationship to each other, cutting elements carried by said wheels for cooperation with related portions of the inner face of the front end portion of said nose-piece, a motor housed in said body, a bearing element extending from said motor, shafts carried by said bearing element and upon which said wheels are mounted for rotation, a crown gear carried by each wheel, and a motor-driven shaft journaled in said bearing member and having a bevel gear meshing with said crown gears, thereby establishing a driving connection between said motor and said wheels.

3. A hair clipping or shaving device as set forth in claim 1 in which the cutting elements are pivoted to the cutting wheels and in which spring means tend constantly to swing said cutting elements to maintain them operatively engaged with the inner face of the front end portion of the nose-piece.
